GEORGE A. SEIB, OF ILION, NEW YORK, ASSIGNEE TO REMINGTON TYPEWRITER COMPANY, OF ILION, NEW YORK, A CORPORATION OF NEW YORK.

TYPE-WRITING MACHINE.

1,289,934.

Specification of Letters Patent. Patented Dec. 31, 1918.

Application filed September 6, 1916. Serial No. 118,607.

To all whom it may concern:

Be it known that I, GEORGE A. SEIB, a citizen of the United States, and resident of Ilion, in the county of Herkimer and State of New York, have invented certain new and useful Improvements in Type-Writing Machines, of which the following is a specification.

My invention relates to typewriting machines, and more particularly to carriage escapement mechanism and to the means for controlling the same.

One of the main objects of my invention is to provide efficient means which enable the printing instrumentalities to be actuated without any resistance from the escapement mechanism at the first portion of the stroke of a type bar and gradually to overcome the resistance of the escapement as it is met in the last portion of the stroke of the type bar. In this manner a light and highly desirable "touch" on the printing keys is provided and such resistance as is offered by the escapement mechanism to the actuation of the printing instrumentalities is presented at a time in the operation of the latter that is felt the least by the operator.

To the above and other ends which will hereinafter appear, my invention consists in the features of construction, arrangements of parts and combinations of devices set forth in the following description and particularly pointed out in the appended claims.

In the accompanying drawings wherein like reference characters indicate corresponding parts in the various views,

Figure 1 is a fragmentary fore and aft vertical sectional view of only so much of a typewriting machine as may be necessary to illustrate my invention in its embodiment therein.

Fig. 2 is a like view showing one of the central type bars and the intermediate connections between the type bars and the dog rocker.

Fig. 3 is a fragmentary rear elevation of the escapement mechanism and some of the associated parts.

Fig. 4 is a fragmentary fore and aft vertical sectional view showing the space key and the connections between the space key and dog rocker.

Fig. 5 is an enlarged detail fragmentary plan view showing the depending arm of the

dog rocker and the parts of the connections from the universal bar and space key which co-act therewith.

Fig. 6 is an enlarged detail left-hand side elevation of the dog rocker and the parts carried thereby, with parts in section.

Fig. 7 is an enlarged detail top plan view of the same.

Fig. 8 is an enlarged detail front elevation of the same.

Fig. 9 is an enlarged detail bottom plan view of the dog rocker and the parts carried thereby.

Fig. 10 is an enlarged detail right-hand side elevation of the same.

Fig. 11 is an enlarged detail rear elevation of the same.

In the present embodiment of my invention the type bars actuate the universal bar but the latter is not taken up by a type bar until late in its stroke and then motion is transmitted from the universal bar to the dog rocker by intermediate leverage changing means by which an actuation of the dog rocker is effected slowly and with the least resistance when it is first set in motion, and the resistance and speed is increased at the last portion of the printing stroke of the type bar, as will hereinafter more clearly appear.

The frame of the machine comprises a base 1 and top plate 2 supported by corner posts, not shown. A suitable power driven carriage (not shown) is mounted above the top plate for movement from side to side of the machine and carries a platen 3 and a feed rack 4. This feed rack meshes with a feed pinion 5 operatively connected with an escapement wheel 6 which in turn co-acts with feed dogs 7 and 8 carried by a dog rocker, designated as a whole by the reference numeral 9. So far as the present invention is concerned it is immaterial what character of escapement devices co-act with the feed dogs, the devices shown in the present instance being the invention of Edwin E. Barney and forming the subject-matter of an application filed by him on the 23rd day of April, 1917, Serial No. 163,963.

The printing instrumentalities or segmentally arranged type bars 10, are pivoted at 11 to a segment 12 and are adapted to strike upwardly and rearwardly against the front face of the platen 3. Any suitable key controlled actuating means may be employed.

to operate the type bars, an illustration of said means being unnecessary for the purpose of my present invention. Each of the type bars works in a guide slot 13 in the 5 segment and is provided with a cam or contact edge 14 which is adapted to co-act with the forward edge 15 of a curved universal bar 16 in the approach of the type bar to the printing position. From an inspection of Figs. 1 and 2, it will be understood that each type bar moves independently of the universal bar during the first portion of the movement of a type bar so that the universal bar and the parts controlled thereby offer no resistance to the printing movement of the type bars until late in the printing stroke of the latter when they have acquired momentum and the resistance offered by the actuation of the 10 escapement mechanism is felt the least by the operator. The universal bar is provided at the central portion thereof with an upwardly projecting lug 17 which has a forwardly extending pin 18 secured thereto. 15 This pin is received in a guide opening in the type bar segment 12 to support and guide the universal bar at the central portion thereof. The universal bar is likewise provided with two rearwardly projecting arms 19 at the sides thereof. The rear ends of their arms are pivoted at 20 to the upper ends of upright crank arms 21 which project upwardly from a rock shaft 22. This rock shaft extends transversely of the machine and is recessed at its ends to receive cone pivot screws 23 received in tapped openings in depending arms 24 which project from the top plate of the machine, each screw being held in its adjusted position by 20 a lock nut 25. In this manner the universal bar is mounted for movement fore and aft of the machine. Arranged centrally of the rock shaft 22 and projecting therefrom is an upright rocking member or crank arm 26 25 provided at its upper end with a headed pin 27 which projects from one side thereof. This pin is received in an open ended slot 28 formed in the forward end of an arm 29 of a substantially horizontally disposed 30 bifurcated actuating member or link designated as a whole by the reference numeral 30. This link is likewise provided with a depending arm 31 which is bent laterally at its lower end to form an offset contact face 32 or abutment 32 which in the normal disposition of the parts is adapted to bear against the actuating arm 26, as shown in Fig. 1. It will be observed that the contact face 32 of the actuating link, in the present instance, 35 is less than one-third the distance from the pivotal axis of the rock shaft 22 that the pin 27 is from said pivotal axis. The purpose of this arrangement will hereinafter more clearly appear.

60 From an inspection of Figs. 1 and 2 it will be seen that the pin 27 in the normal disposition of the parts does not engage the end wall 33 of the slot 28 but is free at this point to move independently of the link 30 until the pin 27 reaches the end wall 33 of 70 the slot. The rear end of the actuating link 30 is apertured to receive a headed stud or pin 34 which projects laterally from one side of the depending actuating arm or member of the dog rocker 9, thus pivotally 75 connecting the actuating link and dog rocker. A returning spring 35 may be connected to the arm 26 to return the rock shaft 22 and the parts connected therewith, including the universal bar 16, to normal position. The forward end of this spring 35 may be connected to any suitably fixed portion of the machine. The dog rocker 9 has a returning spring 36 connected therewith and by which the dog rocker and the actuating link 30 may be returned to normal position.

65 From the foregoing description it will be understood that an actuation of a type bar will result in the movement of the latter being effected first independently of the universal bar throughout a considerable portion of its stroke or until the type bar reaches, say, by way of example, the full line position indicated in Fig. 2, when the engaging edge 90 14 of the type bar contacts with the forward edge of the universal bar and moves the latter rearwardly. This movement of the universal bar transmits movement to the rock shaft 22 and to the crank arm 26 carried 95 thereby, moving the pin 27 rearwardly in the slot 28 until it reaches the rear end wall 33 of the slot. During this movement of the universal bar motion is transmitted to the actuating link 30 solely through the depending arm 31 of the latter by the engagement 100 of the actuating arm 26 therewith. It will be understood, therefore, that motion thus transmitted to the actuating link 30 is effected by a short lever arm, which in effect 105 corresponds to the distance from the pivotal axis of the rock shaft 22 to the point of engagement between the actuating arm 26 and the contact face of the arm 31. It follows 110 that the movement transmitted to the link 30 through its arm 31 is relatively slight and slow and offers but slight resistance. When, however, the pin 27 reaches the end of the slot a relatively fast motion is transmitted to the link through said pin and as the movement of the link continues the contact face 32 will be withdrawn from the actuating arm 26, the motion of the link being effected 115 wholly through the engagement of the pin 27 with the link, and by a lever arm which in effect corresponds to the distance of the pin 27 from the pivotal axis of the rock shaft. I have attempted, by way of example, to represent diagrammatically in Fig. 2 the positions of parts of the construction at three 120

65 From an inspection of Figs. 1 and 2 it will

different periods in the stroke of the type bar, the first represented at *a*, indicating the normal positions of the universal bar and parts controlled thereby, and the instant 5 when the type bar reaches the full line position and is about to take up and actuate the universal bar. The second position, diagrammatically represented at *b*, is that where the type bar has moved the universal bar a 10 distance sufficient to bring the pin 27 to the end of the slot 28, and a comparatively slight movement of the dog rocker has been effected by the actuation of the link 30 through the depending arm 31 thereof. The third position, 15 diagrammatically represented and indicated by *c*, is the final position of the parts when the type bar has reached the printing position and the movement of the dog rocker has been completed through the engagement 20 of the pin 27 with the end of the slot 28. It will be understood that by this construction I provide a two-point successive engagement between the cooperative engaging members 26 and 30; the points of contact between said 25 members being at different elevations and at successively greater distances from the rock shaft 22 as the universal bar moves from its normal position. Therefore, I automatically vary the leverage of the actuating connections 30 between the universal bar and dog rocker in such a manner that the dog rocker is set in motion by a relatively slow movement; that the resistance to the movement of the dog rocker by the universal bar is least 35 at the first portion of the stroke of the latter, and that both the speed and resistance increase at the last portion of the printing movement of the type bar, and at a time when the parts have been set in motion and 40 the increased resistance will be felt the least by the operator. In this manner I am enabled to provide a highly efficient means for controlling the escapement mechanism, and means which offers but little resistance to 45 the operation of the printing instrumentalities, thus providing a light and desirable "touch".

In the present instance means are provided by which the dog rocker may be actuated from the universal bar independently 50 of the space key and the separate and distinct connections therefrom to the dog rocker, and by which the latter is actuated from the space key. Referring more particularly to Fig. 4, it will be seen that the space key or bar 37 is connected near its end to key levers 38 which are fulcrumed at 39 on brackets 40 secured to the base of the machine. These space key levers are connected by a cross bar 41 provided with an opening 42 through which an upwardly extending link 43 passes freely. The lower end of this link is threaded to receive a nut 44 nicked at 45 for co-operation with a straddle screw driver. The upper end of the

link is detachably connected to a two-part actuating member or lever, designated as a whole by the reference numeral 46. This actuating member has one part 47 thereof pivoted at 48 to a bracket 49 secured by 70 screws 50 to the top plate of the machine. The second part 51 of the two-part member is slotted at 52 to receive the shanks of headed screws 53. These screws are received in tapped openings in the part 47, 75 the heads of the screws bearing against the part 51 and clamping it in its adjusted position on the part 47. In this manner the member 46 may be lengthened or shortened to provide for its proper adjustment of its 80 free end relatively to the dog rocker, for reasons which will hereinafter more clearly appear. A contractile spring 54 is connected at one end to the bracket 49 and is connected at its opposite end to the part 51 of 85 the actuating member 46, tending to elevate said member. Projecting rearwardly from the part 51 is a finger 55 provided with an upper horizontally arranged contact face or edge 56. A cam or inclined face 57 is 90 likewise formed on the rear edge of the part 51, the lower end of said cam terminating at the forward end of the contact face 56. The thickness of the member 51 is such that it may be received in the peripheral groove 95 of a headed stud, pin or projection 58 which projects from that side of the depending arm of the dog rocker opposite the side that carries the projection or headed pin 34, as best shown in Fig. 5. From an inspection 100 of Fig. 4 it will be understood that in the normal position of the parts the pin 58 is received in the recess formed between the finger 55 and the cam 57 and at the junction of the two.

The operation of the escapement through an actuation of the universal bar is effective to move the lower end of the dog rocker rearwardly from its normal position, and at this time the dog rocker moves independently of 110 the space key and the intermediate connections between the space key and the dog rocker. Thus, as the dog rocker moves rearwardly the contact face 56 of the two-part actuating member 46 bears upwardly against 115 the pin 58 and there is no movement of the member 46 and the connections from said member to the space key. By reason of this fact the weight of the space key and the intermediate actuating connections between it 120 and the dog rocker offer no resistance to the actuation of the escapement. A depression of the space key is effective to pull the link 43 down, thus actuating the member 46 so that the cam 57 is effective to cam the lower 125 end of the dog rocker rearwardly to effect an actuation of the escapement mechanism. It will be understood, moreover, that the actuation of the dog rocker thus effected is produced independently of the universal 130

bar, and independently of the rock shaft 22 and the parts carried thereby; the link 30 at this time receiving a movement with the dog rocker away from the crank arm 26 by 5 reason of the pin and slot connection 27-28 between the arm 26 and the link 30.

For the purpose of the present invention the connections between the space key and the dog rocker may be of any suitable construction but preferably of such construction as to enable the dog rocker to be actuated independently thereof by the universal bar. The specific means shown and described in the present instance for actuating 10 the dog rocker from the space key are not my invention but are the invention of Elbert S. Dodge and constitute the subject-matter of a separate application filed of even date herewith and bearing Serial No. 118,675.

20 In accordance with my present invention I have provided a dog rocker, the body portion 59 of which is preferably of plate-like formation with trunnions 60 and 61 formed thereon. The formation of this dog rocker 25 is such that it may be, and preferably is, formed by drop forging and case hardening instead of being formed as a casting, as has been common heretofore. The fixed feed dog 8 is preferably formed from the body 30 portion of the dog rocker and is case hardened with it and is provided with a beveled working face 62. The body portion of the rocker is slotted at 63 where it is enlarged and tapped to receive a set screw 64. This 35 set screw constitutes an adjustable stop which co-acts with a stop 65 carried by the bracket 66 which supports the dog rocker. The stops 64 and 65 are arranged above the 40 pivotal axis of the dog rocker and co-act to arrest it in its movement from the normal 45 position. The dog rocker is also slotted at 67 where it is tapped to receive a set screw 68 which coöperates at its forward end with a stop 69 carried by the bracket plate 66. A set screw 73 is received in a 50 tapped opening in each bearing 72 and bears at its inner end against the associated pin 71 to hold it in its adjusted position. The bracket plate 66 may be secured to the top plate of the machine by screws 74 which 55 extend through openings in the foot piece 75 of the bracket plate. The loose dog 7 is formed on one end of a lever 76 which is pivoted intermediate its ends and is provided with an elongated hub-like bearing 60 portion 77 through which a headed pin 78 extends to provide a pivot bearing for the loose dog. This pivot pin extends through the body portion of the rocker and through a bearing sleeve 79 formed thereon. A set 65 screw 80 is received in a tapped opening in

the body portion of the dog rocker and bears at its inner end against the pivot pin 78 to retain it in its adjusted position. A screw 81 is received in a tapped opening in the trunion 61 and extends downwardly therefrom to provide a connection for the rear end of the returning spring 36, the forward end of said spring being connected to a bracket arm 82 secured by screws 83 to the bracket plate 66. A contractile spring 84 is 75 connected at one end to a pin 85 projecting from the body of the dog rocker and at its opposite end, as at 86, to the lower end of the loose dog, or the lever 76 which forms part thereof. The force of this spring is 80 exerted to normally maintain the loose dog in its advanced position against a pin 87 projecting from the forward face of the dog rocker.

An important feature of the present invention consists of the means by which an adjustment may be effected of the depending actuating member or arm of the dog rocker relatively to the body portion thereof in order to regulate the "pull" of the dog rocker. 90 This construction comprises an arm 88 pivoted at its upper end by a pivot screw 89 to the dog rocker and above the pivotal center thereof. The arm 88 is preferably formed as shown with its pivoted end received in a cut-out portion or recess 90 in the body of the dog rocker. The pivot screw 89 of this arm is so constructed that when the screw is loose it will permit a pivotal adjustment of the arm around the screw as 95 a center, but when the screw is tightened its head will bind against the arm and tend to hold the arm in the position to which it has been adjusted. The lower end of the arm 88 carries the pins 34 and 58 hereinbefore described, and by which operative connection is effected between the space key and the dog rocker and between the universal bar and the dog rocker, these pins projecting from opposite sides of the arm as best shown in 100 Figs. 5, 8 and 11. The arm 88 intermediate the ends thereof is apertured to receive freely therethrough the stem of a set screw 91, the body portion of the arm bearing against the underside of the head of said 105 screw, as shown in Figs. 1, 6 and 10. The stem of the screw 91 is received in a tapped opening in the dog rocker at a point where it is slotted at 92. Intermediate the body of 110 the dog rocker and the arm 88 and surrounding the stem of the adjusting screw 91 is a coiled expansion spring 93, the forward end of which is received in a recess 94 formed in the dog rocker and the rear end of which bears against the arm 88. It will be understood that when the screw 89 is loose an adjustment of the arm 88 relatively to the body of the dog rocker may be effected by the screw 91. Thus by turning the screw 91 forwardly the arm 88 will be swung for- 115 120 125 130

wardly around its pivot screw 89, whereas by backing up the screw 91 the arm will be turned rearwardly around the pivot screw 89 by the spring 93. Thus a fore and aft adjustment of the lower end of the depending arm 88 may be readily effected from the rear of the machine by turning the screw 91 in one direction or the other. By adjusting the arm 88 of the dog rocker in the manner described, its point of connection with the train of connections to the universal bar may be regulated without varying the position of the dog rocker to the escapement wheel. Otherwise expressed, the arm 88 may be adjusted to compensate for any variations that may exist in the train of connections between the universal bar and the dog rocker in different machines without varying the position of the dog rocker in its proper adjustment relatively to the escapement wheel. It will be understood from an inspection of Figs. 1 and 4 that the operative movement of the dog rocker from its normal position, whether it is actuated by the space key or by a printing key, is exerted rearwardly on the depending arm of the dog rocker and that the thrust thus exerted is taken by the head of the screw 91 and not by the binding action of the screw 89, so that there is little liability of the arm 88 being displaced from its adjusted position relatively to the body of the dog rocker, positively held as it is on one side by the head of the screw to receive the operating thrust, and the spring 93 resisting an independent movement of the arm in the opposite or return direction.

It will be understood that an adjustment of the arm 88 relatively to the body of the dog rocker requires a corresponding adjustment of the connections between the dog rocker and the space key. For this reason there is a relative adjustment between the two members 47 and 51 of the two-part actuating device 46. This adjustment enables the member 51 to be adjusted fore and aft of the machine to compensate for the adjustment of the arm 88 and so that the cam 57 may always bear the same relation to the pin 58, irrespective of the position to which said pin may be adjusted with the arm 88.

The term "dog rocker" is employed herein in a generic sense and is intended to cover a dog carrier or holder however constructed or mounted.

What I claim as new and desire to secure by Letters Patent, is:—

1. In a typewriting machine, the combination of a type bar, a universal bar actuated by the type bar, a dog rocker, and intermediate actuating connections between said universal bar and dog rocker, said connections comprising arms which extend rearwardly from said universal bar, a rock shaft having upwardly extending arms to which the

arms on the universal bar are connected, a centrally disposed arm on said rock shaft, and a link which extends rearwardly from said centrally disposed arm to the dog rocker.

2. In a typewriting machine, the combination of a type bar, a universal bar actuated by the type bar, a dog rocker, and intermediate actuating connections between said universal bar and dog rocker, said connections comprising an upright rocker arm connected with the universal bar, and a link operative on the dog rocker and having contact points at different elevations and at different distances from the pivotal center of said upright rocker arm, engagement between the rocker arm and link being effected at successively greater distances from the pivotal center of the rocker arm as the universal bar moves from its normal position.

3. In a typewriting machine, the combination of a type bar, a universal bar actuated by the type bar, the type bar moving at the first portion of its stroke independently of the universal bar, a dog rocker, and intermediate actuating connections between said universal bar and dog rocker, said connections including an upright rocker arm connected with the universal bar, and a link operative on the dog rocker and having contact points at different elevations and at different distances from the pivotal center of said upright rocker arm, engagement between the rocker arm and link being effected at successively greater distances from the pivotal center of the rocker arm as the universal bar moves from its normal position, whereby the type bar is first actuated without resistance from the universal bar and the resistance to the movement of the latter by the dog rocker is least at the first part of the movement of the universal bar.

4. In a typewriting machine, the combination of a universal bar, a dog rocker, and intermediate actuating connections between the universal bar and dog rocker, said connections comprising two members one connected with the dog rocker and the other with the universal bar, a pin and slot connection between said members and a contact on one member normally engaging the other member to transmit movement thereto before the pin reaches the end of the slot and is effective to transmit movement from one member to the other.

5. In a typewriting machine, the combination of a universal bar, a dog rocker, and intermediate actuating connections between the universal bar and dog rocker, said connections comprising a rocker arm, a link, a pin and slot connection between said arm and link, and a contact on the link normally engaging said arm and transmitting movement from one to the other before the pin reaches the end of the slot and is effective to transmit the movement.

6. In a typewriting machine, the combination of a universal bar; a dog rocker; and intermediate connections between said universal bar and dog rocker, said connections comprising arms extending from the universal bar, a rock shaft, arms on said rock shaft with which the arms on the universal bar are connected, an actuating member on said rock shaft, a second co-acting actuating member operatively connected with the dog rocker, a pin and slot connection between said actuating members, and a contact on said second actuating member which normally engages the first mentioned member to effect a transmission of movement from one member to the other before the pin reaches the end of the slot and is effective to transmit movement from one member to the other.
7. In a typewriting machine, the combination of a universal bar; a dog rocker; intermediate connections between said universal bar and dog rocker, said connections comprising arms extending from the universal bar, a rock shaft, arms on said rock shaft with which the arms on the universal bar are connected, an actuating member on said rock shaft, a second co-acting actuating member operatively connected with the dog rocker, a pin and slot connection between said actuating members, and a contact on said second actuating member which normally engages the first mentioned member to effect a transmission of movement from one member to the other before the pin reaches the end of the slot and is effective to transmit movement from one member to the other, said members being separable to afford an actuation of the dog rocker independently of the universal bar; and a space key connected to said dog rocker through independent connections, whereby an actuation of the dog rocker may be effected by the space key independently of the universal bar.
8. In a typewriting machine the combination of a universal bar; a dog rocker; intermediate actuating connections between the universal bar and dog rocker, said connections comprising two members one connected with the dog rocker and the other with the universal bar, a pin and slot connection between said members, and a contact on one member normally engaging the other member to transmit movement thereto before the pin reaches the end of the slot and is effective to transmit movement from one member to the other, said members being separable to afford an actuation of the dog rocker independently of the universal bar; and a space key connected to said dog rocker through independent connections, whereby an actuation of the dog rocker may be effected by the space key independently of the universal bar.
9. In a typewriting machine, the combination of a universal bar; a dog rocker; and intermediate connections between said universal bar and dog rocker, said connections comprising arms extending from the universal bar, a rock shaft, arms on said rock shaft with which the arms on the universal bar are connected, a crank arm on said rock shaft, a link pivoted to the dog rocker and connected by a pin and slot connection with said crank arm, and a depending arm on said link which co-acts with said crank arm nearer to the rock shaft than said pin and slot connection and normally engaged by said crank arm, so that said link is moved first through the depending arm and then through the pin and slot connection.
10. In a typewriting machine, the combination of a universal bar; a dog rocker; intermediate connections between said universal bar and dog rocker, said connections comprising arms extending from the universal bar, a rock shaft, arms on the rock shaft with which the arms on the universal bar are connected, a crank arm on said rock shaft, a link pivoted to the dog rocker and connected by a pin and slot connection with said crank arm, and a depending arm on said link which co-acts with said crank arm nearer to the rock shaft than said pin and slot connection and is normally engaged by said crank arm, said link being movable independently of said crank arm; and a space key connected to the dog rocker through independent connections, whereby the dog rocker may be actuated from the space key independently of said rock shaft and universal bar.
11. In a typewriting machine, the combination of a universal bar; an upwardly and rearwardly swinging type bar operative to actuate the universal bar but movable independently thereof during the first portion of the stroke of the type bar; a dog rocker; and intermediate actuating connections between said universal bar and dog rocker and operative on the dog rocker from the beginning to the end of the stroke of the universal bar, said connections comprising an upright rocking member, and a substantially horizontally disposed link bifurcated at one end to form two arms which co-act successively with said rocking member at different distances from the pivotal center thereof and provide a two-point variation in the leverage as motion is transmitted from the universal bar to the dog rocker.
12. In a typewriting machine, the combination of a universal bar; an upwardly and rearwardly swinging type bar operative to actuate the universal bar but movable independently thereof during the first portion of the stroke of the type bar; a dog rocker; and intermediate actuating connections between said universal bar and dog rocker and op-

- erative on the dog rocker from the beginning to the end of the stroke of the universal bar, said connections comprising an upright rocking member, and a substantially horizontally disposed link bifurcated at one end to form two arms which co-act successively with said rocking member at different distances from the pivotal center thereof and provide a two-point variation in the leverage as motion is transmitted from the universal bar to the dog rocker and enable a relative independent movement between the link and rocking member to be effected so as to afford an actuation of the dog rocker independently of the universal bar. 10
13. In a typewriting machine, the combination of a universal bar; an upwardly and rearwardly swinging type bar operative to actuate the universal bar but movable independently thereof during the first portion of the stroke of the type bar; a dog rocker; intermediate actuating connections between said universal bar and dog rocker and operative on the dog rocker from the beginning 20 to the end of the stroke of the universal bar, said connections comprising an upright rocking member, and a substantially horizontally disposed link bifurcated at one end to form two arms which co-act successively with said rocking member at different distances from the pivotal center thereof and provide a two-point variation in the leverage as motion is transmitted from the universal bar to the dog rocker and enable a relative independent movement between the link and rocking member to be effected so as to afford an actuation of the dog rocker independently of the universal bar, an actuating member adjustable on the dog rocker, and a pivotal connection between said link and the adjustable actuating member; a space key; and separate and independent connections from said space key to said adjustable actuating member. 30
14. In a typewriting machine, the combination of a universal bar; an upwardly and rearwardly swinging type bar operative to actuate the universal bar but movable independently thereof during the first portion of the stroke of the type bar; a dog rocker; and intermediate actuating connections between said universal bar and dog rocker, said connections comprising an upright rocking member, a substantially horizontally disposed link bifurcated at one end to form two arms which co-act successively with said rocking member at different distances from the pivotal center thereof and provide a two-point variation in the leverage as motion is transmitted from the universal bar to the dog rocker, one arm of the link having a pin and slot connection with the rocking member and the other arm of the link having a contact face that bears against the rocking member, thus affording a relative independent movement between the link and rocking member. 40
15. In a typewriting machine, the combination of a universal bar; an upwardly and rearwardly swinging type bar operative to actuate the universal bar but movable independently thereof during the first portion of the stroke of the type bar; a dog rocker; and intermediate actuating connections between said universal bar and dog rocker and operative on the dog rocker from the beginning 50 to the end of the stroke of the universal bar, said connections comprising an upright rocking member, a substantially horizontally disposed link bifurcated at one end to form two arms which co-act successively with said rocking member at different distances from the pivotal center thereof and provide a two-point variation in the leverage as motion is transmitted from the universal bar to the dog rocker, an actuating member adjustable on the dog rocker, and a pivotal connection between said link and the adjustable actuating member. 60
16. In a typewriting machine, the combination of a dog rocker, an actuating arm pivoted to the body of the dog rocker and through which motion is transmitted to the dog rocker, a screw for controlling the adjustment of said arm around its pivot, and an actuating device operatively connected to said arm. 70
17. In a typewriting machine, the combination of a dog rocker, an actuating arm pivoted to the body of the dog rocker and through which motion is transmitted to the dog rocker, a spring which tends to turn said arm in one direction around its pivot, a screw which co-acts with said arm and resists the force of said spring and controls 80
18. In a typewriting machine the combination of a dog rocker, an actuating arm pivoted to the body of the dog rocker and through which motion is transmitted to the dog rocker, a spring which tends to turn said arm in one direction around its pivot, a screw which co-acts with said arm and resists the force of said spring and controls 90
19. In a typewriting machine, the combination of a dog rocker, an actuating arm pivoted to the body of the dog rocker and through which motion is transmitted to the dog rocker, a spring which tends to turn said arm in one direction around its pivot, a screw which co-acts with said arm and resists the force of said spring and controls 100
20. In a typewriting machine, the combination of a dog rocker, an actuating arm pivoted to the body of the dog rocker and through which motion is transmitted to the dog rocker, a spring which tends to turn said arm in one direction around its pivot, a screw which co-acts with said arm and resists the force of said spring and controls 110
21. In a typewriting machine, the combination of a dog rocker, an actuating arm pivoted to the body of the dog rocker and through which motion is transmitted to the dog rocker, a spring which tends to turn said arm in one direction around its pivot, a screw which co-acts with said arm and resists the force of said spring and controls 120
22. In a typewriting machine, the combination of a dog rocker, an actuating arm pivoted to the body of the dog rocker and through which motion is transmitted to the dog rocker, a spring which tends to turn said arm in one direction around its pivot, a screw which co-acts with said arm and resists the force of said spring and controls 130

the adjustment of the arm around its pivot, and an actuating device operatively connected to said arm.

19. In a typewriting machine, the combination of a dog rocker, an actuating arm pivoted to the dog rocker by a binding screw which when tightened holds said arm in the position to which it may be adjusted around its pivot on the dog rocker, and an actuating device operatively connected with said arm to actuate the dog rocker.

20. In a typewriting machine, the combination of a dog rocker, an actuating arm pivoted to the dog rocker by a binding screw which when tightened holds said arm in the position to which it may be adjusted around its pivot on the dog rocker, a spring which tends to turn said arm in one direction around its pivot, a screw which co-acts with said arm and resists the force of said spring and controls the adjustment of the arm around its pivot, and an actuating device operatively connected to said arm.

21. In a typewriting machine, the combination of a dog rocker, an actuating arm pivotally adjustable on the body of the dog rocker, a universal bar, connections from said universal bar to said actuating arm, a space key, and separate and independent connections from said space key to said actuating arm.

22. In a typewriting machine, the combination of a dog rocker, an actuating arm pivotally adjustable on the body of the dog rocker, a universal bar, connections from said universal bar to said actuating arm, said connections including a link pivoted to said actuating arm, a space key, and separate and independent connections from the space key to the actuating arm, said last mentioned connections including a pivoted member operative on said arm.

23. In a typewriting machine, the combination of a dog rocker, an actuating arm pivoted to the dog rocker by a binding screw which when tightened holds said arm in the position to which it may be adjusted around its pivot on the dog rocker, a universal bar, connections from said universal bar to said actuating arm, a space key, and separate and independent connections from said space key to said actuating arm.

24. In a typewriting machine, the combination of a dog rocker, an actuating arm pivoted to the body of the dog rocker and through which motion is transmitted to the dog rocker, a spring which tends to turn said arm in one direction around its pivot, a screw which co-acts with said arm and resists the force of said spring and controls the adjustment of the arm around its pivot,

a universal bar, connections from said universal bar to said actuating arm, a space key, and separate and independent connections from said space key to said actuating arm. 65

25. In a typewriting machine, the combination of a dog rocker, an actuating arm pivoted to the dog rocker by a binding screw which when tightened holds said arm in the position to which it may be adjusted around its pivot on the dog rocker, a spring which tends to turn said arm in one direction around its pivot, a screw which co-acts with said arm and resists the force of said spring and controls the adjustment of the arm 75 around its pivot, a universal bar, connections from said universal bar to said actuating arm, a space key, and separate and independent connections from said space key to said actuating arm. 80

26. In a typewriting machine, the combination of a universal bar adapted to be actuated by the type bars, a dog carrier, and intermediate interrupted two-point actuating means whereby the dog carrier is first 85 started at a slow speed and then caused to move, in order to complete its movement, at a higher speed.

27. In a typewriting machine, the combination of a universal bar adapted to be actuated by the type bars, a dog carrier, a member having two contact points with an intervening gap, and a lever adapted to engage said points one after the other. 90

28. In a typewriting machine, the combination of a universal bar adapted to be actuated by the type bars, a dog carrier, a lever having a two-armed member connected to the dog carrier, one arm of said member to be engaged by one part of the lever and 100 the other arm by another part of the lever in succession.

29. In a typewriting machine, the combination of type bars, a universal bar actuated thereby, the type bars being operative first 105 independently of the universal bar, an actuating member operatively connected to the universal bar and operated thereby, a dog rocker, a connecting member carried by the dog rocker, means for adjusting said last 110 mentioned member to different set positions on the dog rocker, a link operatively connected to said adjustable member, and a pin and slot connection between said link and said actuating member. 115

Signed at Ilion, in the county of Herkimer and State of New York, this 2nd day of September, A. D. 1916.

GEORGE A. SEIB.
